UNITED STATES PATENT OFFICE.

EDGAR W. HAZAZER, OF NEW YORK, N. Y.

ELECTRIC SIGNAL.

1,397,582.

Specification of Letters Patent.

Patented Nov. 22, 1921.

Application filed July 14, 1916. Serial No. 109,241.

To all whom it may concern:

Be it known that I, EDGAR W. HAZAZER, a citizen of the United States, residing at New York city, county of New York, and State of New York, have invented certain new and useful Improvements in Electric Signals, fully described and represented in the following specification and the accompanying drawings, forming a part of the same.

10 This invention relates to certain improvements in signals of that class embodying a diaphragm which is vibrated by electric current. While the invention may be used and is intended for use with direct current circuits in which the current is interrupted by suitable interrupting devices, it has been especially designed for use in electric circuits where the current is alternating and the invention will be described as used in such 20 circuit.

Alternating current electric systems as now generally designed deliver power to the consumer with a current having about 120 impulses, that is, flow from maximum to zero, per second. While such current, when used to actuate a diaphragm, will produce a sound, the vibrations are not sufficiently rapid to produce the desired pitch when the sound is produced for the purpose of giving 25 an alarm, as, for instance, a fire alarm, in factories or other buildings, or for signaling purposes generally, and this particularly when diaphragms of relatively small size are used.

30 It is the object of the present invention to produce an improved construction to improve the quality and pitch of the sound produced by a vibrating diaphragm of convenient size, vibrated by the usual alternating current supplied from power houses, by causing the diaphragm to be vibrated between the current impulses, thus increasing the number of vibrations per second of the diaphragm.

40 45 It is a further object of the invention to provide such a construction which shall be simple, cheap to construct, and of convenient form and size for use where desired.

For a full understanding of the invention

a detailed description of a construction embodying the same will be given in connection with the accompanying drawings, in which—

50 Figure 1 is a plan view of the improved device;

Fig. 2 is a vertical sectional view of the 55 construction shown in Fig. 1, taken on line 2—2 of that figure, and showing the device secured to a convenient support;

Fig. 3 is a sectional view taken on the line 60 3—3 of Fig. 2, and

Fig. 4 is a diagrammatic showing of an 65 electric circuit employed for actuating the signal.

Referring now to these drawings, the device includes a diaphragm 1 which, as usual, 70 is in the form of a thin metallic plate or disk held between the front and back sections 2, 3 of the diaphragm case, the diaphragm being clamped between the sections as is usual by clamping screws 4 passing through the margins of the sections 2, 3 of the case and the marginal part of the diaphragm.

75 This diaphragm is vibrated from a suitable source of alternating current receiving a vibration for each current impulse. In accordance with the invention, this diaphragm will also be vibrated between each current impulse so that the vibrations of the diaphragm will be doubled and thus produce a sound having a pitch higher than would be 80 produced were the diaphragm vibrated by the alternating current impulses only. The various connections for effecting this may, of course, be varied. In the particular construction illustrated, however, the diaphragm is vibrated at each current impulse through a magnet 5 having a pole-piece 6 which, if desired, may as shown be made of a number of laminæ, the magnet being in a circuit *a*, *b* of an alternating current, this 85 magnet actuating an armature 7 at each current impulse to cause the vibration of the diaphragm. The means employed for increasing the vibration of the diaphragm and causing it to vibrate between current impulses may be somewhat varied, but a convenient construction is that shown in which 90 the armature is caused to do this through 95

mechanical connections. As illustrated, the armature 7 is a rocking armature, being pivotally supported, as at 8, in frames 9, in which also is secured the magnet 5. This 5 rocking armature 7 is provided at each side of its pivot point with bearing faces 10, 11, and is rocked in one direction by the current impulse actuating the magnet 5, this impulse causing the bearing face 10 to vibrate the diaphragm at each current impulse. The armature is rocked in the other direction between each current impulse to cause the bearing face 11 to vibrate the diaphragm at such time through suitable 10 mechanical connections which, in the best constructions, will include a spring 12. This spring is preferably a flat spring having a slightly bent end 13 which contacts with the bearing face 10 before referred to and against 15 the tension of which spring the armature is rocked by the magnet during a current impulse. When the current impulse is at zero, and the magnet is consequently not energized, the spring 12 rocks the armature in 20 the opposite direction and causes the bearing face 11 of the armature to vibrate the diaphragm during such current lapse, thus doubling the vibrations of the diaphragm and producing a higher pitched sound. In 25 the best constructions, a second flat spring 14 will be provided which contacts with the bearing face 11, this spring assisting the magnet in rocking the armature during the current impulse, though it will be understood 30 that such spring 14 is not essential to the operation of the device and may be omitted if desired. Where springs such as 12, 14 are employed for rocking the armature, they will be secured so that their tension may be adjusted. In the particular 35 construction illustrated, they are secured by screws 15 at one of their ends to the inner face of the diaphragm casing member 3, before referred to, and there are provided adjustable screws 16 passing through the outer face of the diaphragm casing member 3 by 40 which the tension of the springs may be regulated.

The rocking armature may be of various 45 configurations, but in the best constructions it will preferably be as shown, that is, formed with a recess having a beveled face 17, and the pole-piece 6 will be provided with a toe 18 adapted to enter this recess. 50 This construction affords a good attracting surface and effects an efficient operation of the armature when the magnet is energized.

If desired, the usual projector or resonator 55 may be employed, suitably secured to the outer face of the diaphragm casing member 2, before referred to.

In the best constructions, to afford a smoother and clearer note, a washer of felt or similar suitable material 21 is used between 60 the armature and the diaphragm. In the

best constructions, furthermore, to increase the vibratory qualities of the diaphragm, there are provided means for slightly bowing in the diaphragm, as shown in Fig. 2. These means may be of any suitable character, but as shown consist of a flat spring 22 which acts to slightly bow in the diaphragm, a bit of felt or other suitable material 23 being inserted between the spring and the diaphragm. 75

The current may be supplied to the device through any suitable connections, as a push button 20 suitably located in the circuit.

While the invention has been shown and described in what is believed to be its most 80 convenient and effective form, it will be understood that changes and variations may be made in the particular form of the armature and in the mechanical connections for rocking the armature between current impulses, and it is understood that such changes and variations may be made without departing from the invention. 85

What is claimed is:

1. In a signal, the combination of a circuit, a magnet in the circuit, a pivoted armature, means for producing electric impulses in the magnet, a diaphragm, and spring means acting to hold the armature normally in a position in which it exerts no pressure 90 on the diaphragm but permitting a rocking movement past such normal position in either direction whereby the armature is caused to vibrate in time with the electric impulses and vibrate the diaphragm at each 95 impulse and between impulses. 100

2. In a signal, the combination of an alternating current circuit, a magnet in the circuit, a pivoted armature, a diaphragm vibrated by the armature on each current impulse, a spring against which the armature is rocked by the current impulse for rocking the armature in the opposite direction to cause the armature to vibrate the diaphragm between current impulses, and a second 105 spring against which the armature is rocked by the action of the first spring. 110

3. In a signal, the combination of an alternating current circuit, a magnet located in the circuit, the pole-piece of which is formed 115 with a projection, a pivoted armature with a recess in which the projection of the pole-piece is arranged to project, a diaphragm vibrated by the magnet on each current impulse, and mechanically operated means for 120 causing the armature to vibrate the diaphragm between current impulses. 125

4. In a signal, the combination of an alternating current circuit, a magnet located in the circuit, a pole-piece which is formed 125 with a projection, a pivoted armature with a recess in which the projection of the pole-piece is arranged to project, a diaphragm vibrated by the magnet on each current impulse, and a spring against which the arm- 130

ture is rocked by the current impulse for rocking the armature in the opposite direction.

5. In a signal, the combination of a circuit, a magnet in the circuit, means for producing impulses in the magnet of a predetermined frequency, a diaphragm, a rocking armature positioned to bearing against the diaphragm substantially centrally thereof, 10 spring means acting to hold the armature

normally in a position in which it exerts no pressure on the diaphragm but permits a movement past the normal position in either direction whereby the armature is caused to vibrate in time with the impulses and vi- 15 brate the diaphragm at each current impulse and between current impulses.

In testimony whereof, I have hereunto set my hand.

EDGAR W. HAZAER.
